UNITED STATES PATENT OFFICE.

D. RANDOLPH KINYON, OF RARITAN, NEW JERSEY, ASSIGNOR OF ONE-HALF TO JOB C. KINYON, OF SAME PLACE.

FRICITION-CLUTCH.

SPECIFICATION forming part of Letters Patent No. 357,608, dated February 15, 1887.

Application filed November 8, 1886. Serial No. 218,304. (No model.)

To all whom it may concern:

Be it known that I, D. RANDOLPH KINYON, a citizen of the United States, residing at Raritan, in the county of Somerset, State of New

5 Jersey, have invented certain new and useful Improvements in Friction-Clutches, of which the following is a specification, reference being had therein to the accompanying drawings.

10 The object of my invention is to provide a friction-clutch which shall present a large frictional surface at such points as shall give the greatest leverage and require a relatively slight movement of the principal elements involved, and will have peculiar means for the prompt adjustment of the parts.

15 The mechanism employed is an improvement upon the Patent No. 281,700, granted to me July 24, 1883, and the construction and 20 operation of said improvement will be herein-after described, and the novel features thereof specifically set forth in the claims, reference being had to the accompanying drawings, in which—

25 Figure 1 is a side elevation of a friction-clutch constructed in accordance with my invention. Fig. 2 is a front view of the same. Fig. 3 is a longitudinal section of the same, and Fig. 4 is a transverse section of the same.

30 Like letters refer to like parts in all the figures.

A represents a shaft, which may be designated as the "driving-shaft," and B a separate shaft, herein designated as the "driven" 35 shaft. To the driving-shaft is keyed, or otherwise secured so as to rotate therewith, a pulley, C, which constitutes one of the principal elements of the clutch. To the driven shaft B is, in like manner, secured a disk, D, 40 which is provided with lugs having slots d , through which bolts e pass loosely, each being provided with a shoulder, (as stated in my Patent No. 281,700,) against which its nut abuts, to prevent binding lengthwise in the 45 slots. The bolts serve to connect to the disk D two half-rings, E, in such a manner that they may move radially in and out upon the disk, and thus be caused to bear upon or be held away from the periphery of the pulley 50 C. Each of the half-rings is provided with

two lugs, e^2 , each pair of lugs being bored to receive a shaft, F, having its ends f turned of smaller diameter and eccentrically to the body of said shaft.

Upon the ends f of the shafts F are journaled the links f^2 , that are longitudinally bored and screw-tapped to receive the ends of the bolts f^3 , that unite said links. These bolts have a right-hand screw-thread cut on one end, and a left-hand screw-thread on the opposite end, and squared at f^4 half-way of their length, to take a wrench, so that the links f^2 can be promptly drawn toward each other, and consequently any undue looseness of the half-rings, occasioned by wear or otherwise, can be easily taken up. A lever, F', projects from each eccentric shaft F, and is connected by a link, G, to the sliding collar H, mounted on the shaft B. Said collar is annularly grooved, as shown, for the reception of any well-known operating-lever.

The operation is as follows: Motion being given to the shaft A is conveyed to the pulley C, fixed thereon; and if the collar H is moved toward the disk D the outer ends of the levers F' are forced apart, and the eccentric shafts F rotated, and as the eccentric ends of said shafts are retained in pairs at regulable distances apart by the bolts f^3 the two half-rings are brought toward each other and firmly against the periphery of the pulley C, and by the friction of these parts upon each other the motion is conveyed to the disk D and the shaft B to which it is affixed. By this construction a slight movement is required of the half-rings, and hence I am enabled to employ the limited but very powerful movement of eccentric clamping devices, as F, and the surface-contact is of such a nature and form as to create great friction without undue strains on the parts.

If desired, the shaft A may be continuous, in which case the disk D would be loosely mounted thereon, and provided with or connected to any suitable belt-pulley to drive any desired mechanism.

Having now fully described my invention, I claim—

1. In a friction-clutch, a driving-shaft and a driven shaft, a pulley, a disk carrying half-

rings, and eccentric shafts adapted to force said half-rings upon the periphery of a pulley mounted upon the driving-shaft, in combination with links carried upon the ends of
5 the eccentric shafts and bolts provided with right and left hand screws upon their ends, substantially as described.

2. The combination of the pulley C, its half-rings, clamps E, having perforated lugs e^2 , the
10 eccentric shafts F, passing through the lugs of each clamp, and the links carried upon the

ends of the eccentric shafts with bolts provided with right and left hand screws upon their ends, substantially as and for the purpose described.

15 In testimony whereof I affix my signature in presence of two witnesses.

D. RANDOLPH KINYON.
